(57) **CLAIM**

The ornamental design for a conductive seal of a biomedical signal recorder, as shown and described.

DESCRIPTION

FIG. 1 is a front view of a conductive seal of a biomedical signal recorder, showing our new design;

FIG. 2 is a rear view thereof;

FIG. 3 is a top view thereof;

FIG. 4 is a bottom view thereof;

FIG. 5 is a right side view thereof, the left side being symmetrical;

FIG. 6 is a cross-sectional view thereof, taken along the line 6-6 of FIG. 1; and,

FIG. 7 is an exploded perspective view thereof, showing a state of separate components of the conductive seal of a biomedical signal recorder.
